United States Patent Office.

BENAIAH FITTS, OF NEWARK, NEW JERSEY.

Letters Patent No. 72,618, dated December 24, 1867.

IMPROVEMENT IN PLANING-MACHINES.

The Schedule referred to in these Letters Patent and making part of the same.

TO ALL WHOM IT MAY CONCERN:

Be it known that I, BENAIAH FITTS, of Newark, State of New Jersey, have invented a new and useful Improvement in Cylinder Planing-Machines; and I do hereby declare that the following is a full, clear, and exact description of the construction and operation of the same, reference being had to the annexed drawings, making a part of this specification, in which—

Figure 1 is an elevation of the machine.

Figure 2 is a plan; showing a section of the gears through $x y$, fig. 1.

The invention relates to certain improvements in the gearing that drives the feed-rolls in machine for planing boards.

The construction is as follows: a is a frame that supports the other parts of the machine; b is the cutting-cylinder; c is the upper feed-roll; d is the lower feed-roll; e is an external gear on lower feed-roll; f is an internal gear on upper feed-roll. It should be made with the side towards the cutting-cylinder closed up, or in disk form, to keep the shavings from filling up the teeth. g is a gear, running in gear e , and to which power is applied to drive the feed-rolls. h is a small gear, running in gear f and gear e , connecting the upper to the lower roll, and by which upper and lower rolls are connected together, and are driven in the direction of the arrows. i is an arm, one end of which is fitted to and held by lower roll-shaft, the other end holding the shaft on which gear h rotates. s is an arm, one end of which is fitted to and held by the upper roll-shaft, the end of which projects far enough through gear f to receive it, the other end holding in position the shaft on which gear h rotates. r is a screw that raises and lowers or holds in place the upper roll c .

The operation is as follows: In planing boards of different thicknesses, the upper roll c is raised and lowered, to correspond with the thickness of the board, carrying with it gear f ; but it will be seen that gear h , being held in position by arms i and s , holds the same relation or relative position to gears f and e at one point that it does at another, thus driving the upper roll whatever distance the rolls c and d may be apart.

I am aware that connecting together of feed-rolls by means of a small gear held in its position by two arms, one connecting the gear-shaft to the upper, the other to the lower roll-shaft, and running in an internal and external gear made fast to the roll-shaft, is not new. Letters Patent were granted me, BENAIAH FITTS, then of Worcester, Massachusetts, in 1857, in which such an arrangement was the peculiar feature; and this invention consists in certain improvements carrying out and perfecting the same. It will be seen that there is one gear less, thus making it more simple. In that, the open side of the internal gear is towards the cutting-cylinder, thus allowing the shavings to fill up the teeth of the gear, and causing much injury. With this, the open side of the internal gear is from the cutting-cylinder, the disk towards it, thus preventing its becoming filled with shavings.

Having set forth the construction and operation of my invention, what I claim as new, and desire to secure by Letters Patent, is—

The arms s and i , when constructed to support the gear-wheel h , and arranged to operate with wheels e and f , substantially in the manner and for the purposes described.

BENAIAH FITTS.
